UNITED STATES PATENT OFFICE

2,255,527

HEATING DEVICE

Sam P. Locke, Mexico, Mo.

Application March 18, 1939, Serial No. 262,658

13 Claims. (Cl. 110—29)

This invention relates to heating devices such as stoves, furnaces, boilers and the like for the burning of solid fuels. More specifically, the invention relates to a magazine type heater for burning solid fuels and having flues adjacent the magazine defined by refractory bricks forming part of the magazine and communicating with the interior of the magazine for receiving combustion gases.

This application is a continuation-in-part of my copending application Serial No. 231,090, filed September 21, 1938.

According to this invention, a sizable reservoir or magazine for solid fuel is provided above the grate in a stove, furnace, or boiler. This magazine is defined in part by spaced opposed refractory slabs extending upwardly from the grate. The outer faces of the refractory slabs are spaced inwardly from a casing so as to define with the casing a pair of vertical flues along the entire length of the fuel magazine. The refractory slabs have passageways therethrough communicating with the flues.

A sizable charge of solid fuel such as coal is dumped into the magazine on top of a fire on the grate. According to this invention, the coal in the magazine can be coked before it burns down to the grate, because the flues provided on both sides of the magazine communicate with the interior of the magazine and allow a draft through the coal.

Any smoke or gases from the heated coal can be completely burned in the flues, and very high combustion efficiency is thus obtained.

Any grade of solid fuel can be used in the magazine, and the same will burn from the bottom and sides of the magazine, so that the inside of the charge is the last to burn. In this manner an efficient heat transfer is obtained.

Since a comparatively heavy refractory slab or brick defines one wall of each flue, heat will be retained therein to produce steady, even heating for prolonged periods.

No "puffing" can occur as is customary in magazine type stoves, because no gases can be entrapped in the magazine.

It is then an object of the invention to provide a heating device for the burning of solid fuels to produce a prolonged uniform heat with a single charge of fuel.

Another object of the invention is to provide refractory slabs or bricks for heating devices capable of defining walls of a fuel magazine with their inner surfaces and walls of flue passageways with their outer surfaces.

Another object of the invention is to provide a heating device having a magazine type fuel chamber and flues in communication with the chamber at various levels therein.

Another object of the invention is to provide

vertical flues in magazine type stoves for coking solid fuel in the magazine before the fuel burns down to the grate.

A specific object of the invention is to provide a single draft stove or furnace having a fuel magazine receiving a part of the draft and also having vertical flues receiving the rest of the draft for completely burning gas and smoke issuing from the magazine.

Another object of the invention is to provide refractory bricks which are easily mounted in standard grate type stoves or furnaces for defining fuel magazines and flues therein.

Other and further objects of the invention will become apparent to those skilled in the art from the following detailed description of the annexed sheets of drawings which disclose preferred embodiments of the invention.

On the drawings:

Figure 1 is a front elevational view of a stove according to this invention;

Figure 2 is an enlarged vertical cross sectional view taken along the line II—II of Figure 1;

Figure 3 is a vertical cross sectional view taken along the line III—III of Figure 2;

Figure 4 is a horizontal cross sectional view taken along the line IV—IV of Figure 1;

Figure 5 is a fragmentary vertical cross sectional view taken along the line V—V of Figure 4;

Figure 6 is a central vertical cross sectional view taken through a hot air furnace according to this invention;

Figure 7 is a horizontal cross sectional view taken along the line VII—VII of Figure 6;

Figure 8 is a vertical cross sectional view taken centrally through a steam boiler according to this invention;

Figure 9 is a horizontal cross sectional view taken along the line IX—IX of Figure 8;

Figure 10 is a rear elevational view of the modified form of refractory brick according to this invention;

Figure 11 is a vertical cross sectional view taken along the line XI—XI of Figure 10.

As shown on the drawings:

In Figures 1 to 4 inclusive, the reference numeral 10 designates a stove according to this invention. The stove 10 is composed of a cylindrical sheet metal body member 11 having a top or dome 12 on the top thereof and a bottom plate 13 closing the bottom thereof. A ring 14 is disposed around the bottom of the cylindrical body member 11 and has an inturned flange or leg 14a supporting and reinforcing the bottom plate 13.

The top 12 has a smoke outlet or chimney 15 provided with a damper 16 therein. The damper 16 is operated from the outside by a handle 17. A fuel door 18 is mounted on the top 12.

An ash door 19 is mounted on the body member 11 near the bottom thereof. The ash door

19 can have draft openings therethrough controlled by a draft wheel 19a mounted on the outer face of the door, as best shown in Figures 1 and 2.

The top 12 and the body member 11 have openings therethrough closed by the doors 18 and 19.

Legs 20 support the stove above the floor. These legs 20 have portions 20a thereof extending upwardly from the bottom of the cylindrical body member 11 to a point above the top of the ash door 19. Bolts such as 21 extend through the top portions of the leg members 20a and through the body member 11, as best shown in Figure 5. The ends of the bolts 21 projecting through the member 11 have nuts such as 21a provided thereon, as shown in Figure 5.

A grate ring 22 is mounted in the cylindrical body member 11 and supported in spaced relation above the bottom 13 of the stove on the nuts 21a, as best shown in Figure 5. As is customary, the grate ring 22 has inwardly extending downwardly sloping fingers 22a around the inner periphery thereof.

As best shown in Figures 4 and 5, the grate ring also has several equally spaced longer fingers 23 extending beyond the fingers 22a for supporting the grate 24 thereon. The grate 24 has fingers 24a projecting therefrom at spaced intervals around the periphery thereof. Draft ports 24b are also formed through the grate.

A shaker arm 25 is provided for shaking the grate 24.

Linings 26 and 27 built up from fire bricks are provided inside of the body member 11 at the front and back of the stove. The linings 26 and 27 can be supported on the grate ring 22 and extend to the top of the body member 11, as shown in Figure 2. The linings 26 and 27 are curved cylindrically with the body member 11 and fit against the inner face of the member.

As best shown in Figure 4, the linings 26 and 27 are in spaced opposed relation and extend only around the front and back surfaces of the member 11.

According to this invention, two bricks or slabs 28 of refractory material bridge the spaces between the linings 26 and 27. The bricks or slabs 28 are flat and have converging edges 28a abutting the ends of the linings 26 and 27, as best shown in Figure 4. The bottoms of the bricks or slabs 28 are supported on the grate ring 22, and the divergent edges of the slabs are adapted to abut against the body member 11 so that the slabs can merely be slid into position between the linings and will be held in an upright position by the body member 11 and the edges of the linings 26 and 27.

Since the body member 11 is cylindrical and since the bricks or slabs 28 are flat, flues or passageways 29 and 30 are provided in the sides of the stove defined by the outer faces of the slabs or bricks and the inner face of the body member 11. These flues extend from the grate to the top 12.

If desired, the grate ring 22 can have a solid, downwardly sloping portion 31 (Figure 4) under the bricks or slabs 28 instead of the usual spaced fingers 22a. This solid portion 31 can choke off some of the air from beneath the grate so that too much air will not enter directly into the flues and will pass through the grate into the fuel magazine M (Figure 3) defined by the linings and slabs.

As best shown in Figures 2 and 3, each slab 75

28 can have a cut-out portion 32 in the bottom thereof. This cut-out portion 32 permits passage of air and combustion gases from the burning mass on the grate 24 into flues 29 and 30. The cut-out portion 32 can be made of a predetermined size in accordance with the blast requirements for the stove.

Vertical slots 33 are also cut through the slabs 28 to provide draft passageways joining the magazine with the flues. As best shown in Figure 4, these slots 33 flare outwardly so that the small ends thereof face the magazine and the large ends thereof face the flues. This outward flare prevents the wedging of fuel particles in the slots, since, if a lump of coal or the like is small enough to pass through the small mouth of the slot facing the magazine, it will fall free out of the larger mouth of the slot facing the flues.

The stove shown in Figures 1 to 4 receives a substantial charge of solid fuel such as coal into the magazine M thereof on top of the burning fuel bed on the grate 24. The fuel charge is readily fed to the stove through the door 18.

Air is supplied through the opening in the ash door 19 in regulated amounts controlled by the draft wheel 19a. This air then rises through the grate slots and spaces between the fingers of the grate and grate ring. The air will aid combustion of the fuel on the grate, and products of combustion will pass through the openings 32 and 33 in the refractory bricks or slabs 28 into the flues 29 and 30. Some air will pass directly from the ash chamber beneath the grate into the flues 29 and 30 between the periphery of the grate and the solid portion 31 of the grate ring under the slabs 28, as shown in Figure 3. This air, together with other unburned air leaving the magazine, will serve to completely burn all incompletely burned gases issuing from the magazine.

The flues 29 and 30 are not insulated from the body member 11, and any burning gases in the flues will radiate heat through the body member 11. If desired, in order to prevent discoloration of the metal sheet forming the body member 11 along the flues 29 and 30, this sheet can be lined with additional metal sheets 34 and 35.

Smoke rising through the magazine into the head 12 of the stove is commingled with the gases from the flues 29 and 30, and since an excess of air is preferably supplied to the flues, this air will burn the smoke so that all products of combustion leaving the smoke outlet 15 will be thoroughly burned.

The solid fuel in the magazine M will burn on the bottom, flue sides, and top thereby giving a big burning area in the stove. The burning will progress inwardly through the body of coal in the magazine, so that the inside of the body is the last to burn. This gives an efficient heat transfer, since the outer portions of the coal body are in intimate contact with heat radiating surfaces. The fire brick linings and the slabs 28 will, of course, become heated and will radiate heat uniformly.

Air can pass through the body of coal in the magazine M in regulated amounts and will be uniformly distributed throughout the body of the coal. In this manner no hot spots are formed and no "puffing" occurs, because the air always has a free path. Clinkers are not formed, because the fuel is heated to temperatures well above the combustion point.

The coal in the magazine will first coke, be-

cause it is heated by the flue gases and also because it receives regulated amounts of air permitting such coking. The coked coal is then completely burned as it drops downwardly toward the grate.

Any grade of coal can be used, and stoves built in accordance with the invention will operate without attention to give a uniform heat for a period of over 48 hours.

The fire brick slabs producing the flues at the sides of the magazine are readily insertable into stove constructions. As shown in Figure 4 of the drawings, these slabs can merely be slid into position between the fire brick linings and need only be supported on the usual grate ring, as shown in Figures 2, 3, and 5.

In Figures 6 and 7, there is disclosed a hot air furnace embodying the principles of this invention. Parts substantially identical with parts described in Figures 1 to 5 have been designated by the same reference numerals.

As shown in Figures 6 and 7, the hot air furnace 40 comprises a stove 10a substantially identical with the stove 10 described in Figures 1 to 5, but not equipped with legs. The stove 10a is surrounded by a metal casing 41 defining an air chamber 42 completely around the sides and top of the stove 10a. The air chamber 42 receives cold air through a duct 43 communicating with the bottom of the chamber and discharges hot air through outlet ducts such as 44 communicating with the top of the chamber.

The top or dome 12 of the stove 10a receives a fuel chute 45 in place of the door 18. The chute 45 extends through the casing 41 and is closed by a door 46.

The ash compartment beneath the grate 24 also receives a chute 47 extending through the air chamber 42 at the bottom thereof and receiving the ash door 19 thereon.

The stove 10a operates identically with the stove 10 described in Figures 1 to 5, but the air surrounding the stove is confined in the chamber 42 and circulated to hot air registers located elsewhere.

In Figures 8 and 9, the reference numeral 50 designates generally a boiler according to this invention. The boiler 50 is composed of a shell member 51 defining a combustion chamber 52 and a water and steam chamber 53 surrounding the combustion chamber 52. The chamber 53 receives water through an inlet 54 communicating with the bottom thereof and discharges steam through an outlet 55 communicating with the top thereof.

The shell 51 is mounted on a base 56 defining an ash chamber 57. The chamber 57 has a clean-out door 58 provided with a draft wheel 58a thereon.

The usual grate ring 59 and grate 60, described in Figures 1 to 5, is provided at the top of the base 56 for forming the bottom of a combustion chamber 52. The combustion chamber 52 communicates with a smoke outlet 61 extending through the shell 51 and communicating with a smoke pipe 62 having a damper 63 therein.

The combustion chamber 52 has a coal chute 64 communicating with the top thereof and extending through the top of the shell 51. The chute 64 is closed by a door 65.

As best shown in Figure 9, the inner wall of the shell 51 defining the combustion chamber 52 is cylindrical and forms the side walls of the combustion chamber. Since these side walls are surrounded by water in the chamber 53, no lining

for these walls is necessary as in the construction shown in Figures 1 to 7.

However, according to this invention, refractory bricks or slabs 66 are bolted on opposite side walls of the combustion chamber 52 by means of bolts 67 extending inwardly from the side walls. The slabs 66 are flat and therefore bridge across two spaced portions of the side walls to define flues 68 and 69 along the sides of a magazine formed by the slabs 66, the grate 60, and the side walls of the combustion chamber. These flues 68 and 69 extend from the grate ring and are similar to the flues 29 and 30 defined in Figures 1 to 7.

As best shown in Figures 10 and 11, the slabs 66 are of a modified form provided with cut off bottom corner portions 70 instead of the cut-out central portions 32 of the slabs 28 and also provided with spaced cut-out edge portions 71 in place of the slots 33.

The outer faces of the slabs are recessed as at 72 and 73 between the aligned cut-away portions 71 on opposite edges thereof. A V-shaped recess 74 is also provided having the pointed base thereof slightly beneath the recess 72 and having the top thereof at the top of the slab.

The modified slabs 66 provide passageways through the cut-out bottom edges 70 and the cut-out edges 71 joining the fuel magazine with the flues. The passageways 71 communicate through the recesses 72 and 73 with the main recess 74, so that larger capacity gas passageways are formed.

The slabs 66 can be used in place of the slabs 28 with fire brick lined stoves such as 10 and 10a, since the cutaway edges 71 will be spaced inwardly from the edges of the lining to form the draft ducts joining the flues with the fuel magazine. Likewise the cut-away bottom edges 70 serve the same purpose as the cut-away central portions 32 of the slabs 28.

Obviously, if desired, the slabs 28 can be used in the boiler construction 50.

From the above descriptions, it should be understood that this invention provides heating devices wherein refractory bricks or slabs cooperate with a combustion chamber to form a fuel magazine and flues at the sides of the magazine. These flues communicate with the fuel magazine through ducts or passageways formed in the refractory slabs. The slabs are readily mounted in standard stoves, furnaces, and boilers and serve to convert such devices into magazine type units for solid fuel.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a heating device having a grate bottom and side walls extending upwardly from the grate, the improvement which comprises a pair of refractory slabs in spaced opposed relation mounted on and extending upwardly from the grate bottom to define a fuel magazine and cooperating with the side walls to define flues alongside of the magazine, said slabs providing passageways joining the interior of the magazine with the flues.

2. In a heating device including a cylindrical body member, a grate ring in said body member, and a grate cooperating with the grate ring, the

improvements which comprise a fire brick lining opposite localized portions of the body member above the grate ring, substantially flat rectangular refractory slabs in said body member extending upwardly from the grate ring and bridging the spaces between the fire bricks to define flues between the body member and the outer faces of the bricks, said slabs cooperating with the fire bricks to define a fuel magazine above the grate, and said slabs providing passageways joining the 10 fuel magazine with the flues.

3. In a stove including a cylindrical body member, a grate ring in said body member, and a grate cooperating with said ring, the improvements which comprise a refractory lining in said body member extending around the front and back portions thereof in spaced opposed relation, substantially flat rectangular slabs of refractory material in said body member bridging the spaces between the lining and extending upwardly from the grate ring, said lining and said refractory slabs cooperating to define a fuel magazine above the grate, and said body member and said slabs cooperating to define flues alongside of the fuel magazine.

4. In a stove including a cylindrical body member having a grate ring therein in spaced relation from the bottom thereof and a grate cooperating with said grate ring, the improvements which comprise refractory linings in the front and back of the body member, substantially flat rectangular refractory slabs in said body member bridging the gap between the linings and cooperating with the linings to define a fuel magazine above the grate, said slabs also cooperating with the body member to define flues alongside of the magazine, spaced legs on the bottoms of said slabs engaging the grate ring to support the slabs and defining an air passageway from the grate to the flues, and said slabs providing additional passageways above the legs thereof joining the fuel magazine with the flues.

5. A heating device comprising a body member having a grate construction therein, a smoke outlet for said body member, a fuel inlet for said body member, an ash outlet for said body member, and spaced opposed refractory slabs in said body member mounted on and extending upwardly from the grate construction on opposite sides of the body member to define a fuel magazine with their inner surfaces and flues with their outer surfaces.

6. A heating device comprising a shell defining a combustion chamber, a grate forming the bottom of the combustion chamber, spaced opposed rectangular refractory slabs in said combustion chamber above said grate, said slabs having inner surfaces defining a fuel magazine and outer surfaces defining flues alongside of the magazine, and said slabs providing passageways joining the magazine with the flues.

7. A refractory slab for heating devices comprising a rectangular body member having a recess in one face thereof extending from the top of the member and converging to a point spaced from the bottom of the member, said face having additional recesses connecting the converging recess with the side edges of the member, and said side edges being indented at the recesses.

8. In a heating device including a cylindrical heat radiating body member, a grate ring secured to said body member in spaced relation to the bottom thereof, and a grate cooperating

5 with the grate ring, the improvements which comprise spaced opposed firebrick linings extending locally around opposite inner sides of said body member from the grate ring to the top portion of the body member, substantially flat rectangular refractory slabs bridging the spaces between the linings and extending upwardly from the grate ring to the top portion of the body member, said slabs having sloping edges for locking against the edges of the lining, said slabs cooperating with the linings to provide a fuel magazine above the grate, said slabs also cooperating with the cylindrical body member to define flues on opposite sides of the fuel magazine, and said slabs having passageways therethrough joining the fuel magazine with the flues.

9. In a heating device, a metal body member, refractory material lining said body member around a portion only of the inner surface thereof, and a substantially flat refractory slab bridging the space in the refractory lining to cooperate therewith for defining a fuel magazine in the body member, the outer face of said slab being spaced from the body member to define a flue therewith communicating with the fuel magazine.

10. A heating device comprising a body member, a grate construction in said body member and carried thereby above the bottom thereof, refractory slabs in said body member on opposite sides thereof above the grate construction defining a fuel magazine with their inner faces, said slabs having outer face portions thereof spaced from the body member to provide flues extending upwardly from the grate construction, communicating with the fuel magazine.

11. A refractory slab for heating devices comprising a rectangular member having spaced dependent legs at the bottom thereof, said member having longitudinal side edges whose entire surfaces lie in planes angularly disposed from the broad faces of the member and converge toward the median plane of the member, and spaced longitudinal slots extending through the broad faces of said member intermediate the top and bottom extremities thereof, the side walls of said slots converging toward one face of said member in the same direction as the surfaces of said longitudinal side edges.

12. A heating device comprising a body member having a grate construction therein, a smoke outlet for said body member, a fuel inlet for said body member, an ash outlet for said body member, and spaced refractories in said body member mounted on and extending upwardly from the grate construction, said refractories having outer faces inwardly of the body member, and said refractories defining a fuel magazine with their inner surfaces and defining passages outwardly of the fuel magazine with their outer surfaces.

13. A heating device comprising a body member, a grate construction in said body member and carried thereby above the bottom thereof, refractory slabs in said body member spaced around the inner periphery thereof above the grate construction to define a fuel magazine with their inner faces, and said slabs having outer face portions thereof spaced from the body member to provide passages extending upwardly from the grate construction and communicating with the interior of the body member.
